G. G. WOLFE.

PARLOR STOVE.

No. 17,236.

Patented Apr. 5, 1887.

UNITED STATES PATENT OFFICE.

GURDON G. WOLFE, OF TROY, NEW YORK, ASSIGNOR TO THE FULLER & WARREN COMPANY, OF SAME PLACE.

DESIGN FOR A PARLOR-STOVE.

SPECIFICATION forming part of Design No. 17,236, dated April 5, 1887.

Application filed April 24, 1886. Serial No. 200,096. Term of patent 7 years.

To all whom it may concern:

Be it known that I, GURDON G. WOLFE, of the city of Troy, county of Rensselaer, State of New York, have invented and produced a 5 new and original Design for the Ornamentation of Parlor-Stoves, of which the following is a specification.

My invention relates to the ornamentation of parlor-stoves, as the same is shown in the 10 accompanying photograph, forming a part of this specification, in which photograph letters are used to designate the parts of the stove and numbers the ornamentation.

The letter T indicates the top ornament of 15 the stove, it taking the place of the usual and ordinary urn.

The numbers 1, 2, 3, 4, and 5 designate jewels in and on the exterior surface of the ornament T.

20 The letter P indicates a panel formed in the end or side of the stove near its top, and the numbers 6, 7, 8, 9, and 10 designate jewels in the said panel, to appear on the exterior surface of the panel, with the finished surface of 25 said jewels as the exterior surface.

The letter F indicates the two upper front corners of the stove, each of which is ornamented with one of the jewels 11 and 12.

The letter C indicates the cap of the front 30 outcurve of the stove, and the numbers 13, 14,

15, 16, 17, and 18 designate jewels, with the cut faces of the jewels the exterior faces.

Having thus described my design, what I claim, and desire to secure by Letters Patent, is—

1. In a design for a stove, the upper end and front panels, consisting of end panels having fretted borders and plain fields and jewels arranged in the fields, and front corner panels having fretted borders and plain fields with 40 jewels arranged within the fields, as shown and described.

2. In a design for a stove, the upper front portion, consisting of the corner panels having fretted borders and plain fields with jewels arranged within the fields, and the cap C, having a plain circular field centrally arranged and jewels set therein, as shown and described.

3. In a design for a stove, the top herein 50 shown and described, consisting of an urn or basin for the top, having a plain field and jewels set therein.

Signed at Troy, New York, this 8th day of March, 1886, in the presence of two witnesses.

GURDON G. WOLFE.

Witnesses:

W. E. HAGAN,
CHARLES S. BRINTNALL.
